UNITED STATES PATENT OFFICE.

ALFRED ELY, OF ROSLYN, NEW YORK.

ILLUMINATED TRAFFIC SIGN.

Application filed March 1, 1924. Serial No. 696,117.

To all whom it may concern:

Be it known that I, ALFRED ELY, a citizen of the United States, and a resident of Roslyn, Long Island, New York, have invented 5 certain new and useful Improvements in Illuminated Traffic Signs, of which the following is a specification.

My invention relates to illuminated signs, and particularly to signs intended to give 10 traffic instructions having a directional characteristic.

Examples of signs embodying my invention are shown in the accompanying drawings, in which Fig. 1 is a perspective of one form 15 of sign; Fig. 2 is a sectional view of the sign shown in Fig. 1; Fig. 3 is a sectional plan view of the base; Fig. 4 is a detail section showing the manner in which the glass sides are held in place, and Fig. 5 is a side 20 view of a modified arrangement.

Referring to the illustrative example shown in Figs. 1 to 4, 2 is a main casing having rolled edges 3. In the particular form illustrated the casing 2 has a pointed 25 end 4. The opposite end may be closed in any desired manner as by the removable end 5.

Adjacent the pointed end 4 is a partition 30 6 which divides the body of the sign into two compartments. The sides of the sign consist of glass plates 7 which slide between the rolled edges 3 and the partition 6 and near the door 5 are held in place by brackets 35 8. Rods 9 are passed through the main casing 2 as a means for supporting the sign.

Within the main casing are positioned two electric lamps 10 which are connected in parallel to the electric circuit passing through 40 fuses 11. Connected to the same circuit is an electric flasher 12 from which the circuit passes to a lamp 13 which illuminates the small pointed compartment formed in the point 4.

45 Running longitudinally along each side plate 7 is a band 14 which preferably is colored. In the present instance this zone is shown as red, with a narrow black stripe along each side; other colors can be used, 50 but the band should be made, either by the use of a body color or a marginal stripe, to contrast with the adjacent portion of the sign. The portions of the plate 7 above and below the band 14 are painted white or otherwise rendered translucent and on the surface 55 are painted traffic instructions. Of course

raised letters can be used in place of painted ones.

The white portion of the plate 7 ends at partition 6, and the portion of the plate 7 60 which forms the sides of the small pointed compartment is painted preferably the same color as the band 14; in this instance it is shown as painted red, bordered by a narrow black stripe. The interior of the casing 2 65 and both sides of the partition 6 are preferably painted white to increase the illumination.

When the electric current is turned on, the main compartment or portion of the sign 70 will be permanently illuminated and will show a zone having a transverse band which contrasts with the rest of the zone and will show lettering adjacent this band. When the lamp 13 lights, the small compartment will 75 be illuminated and the corresponding end of plate 7 will shine out in the form of an arrow-head, thus attracting particular attention to itself and designating the direction referred to in the traffic instructions. In 80 this example, the instructions consist of the words "One Way Street" and the arrow is intended to be pointed in the direction in which traffic is allowed to pass.

I find it advantageous, though not always 85 necessary, to illuminate the small compartment to a greater extent in proportion to its size than the rest of the sign, so that when the pointed end flashes, particular attention 90 will be attracted to that feature. For example if the sign is of the proportions shown, the lamps 10 and the lamp 13 can all be made with the same candle-power, which will result in the small compartment being 95 the more brilliantly illuminated.

By this arrangement I provide a sign which can easily be read either in the day-time or at night and which at night attracts attention to itself by the fact that a portion flashes, and in particular attracts 100 attention to that portion which indicates the directional characteristic of the traffic instruction.

In the form of device shown in Fig. 5 the 105 casing 2' is made rectangular and is divided into three compartments by the partitions 6' and 6''. In this arrangement there are two bands 14' corresponding to the single band 14 described above, but the portion of the glass plates covering the two end sections are painted black, except that each 110 has two portions painted the same color as

the bands 14', one such portion defining an arrow-head and the other portion defining the tail of an arrow. This arrangement is particularly useful for sign posts where the traffic instructions in part have a directional characteristic in one way and in part in another way. As before, it is intended that the compartments defining the arrow-heads shall be illuminated by lamps which will 19 flash on and off intermittently.

It is to be understood that the foregoing examples are given by way of illustration only and that many modifications may be made without departing from the spirit of 15 my invention.

What I claim is:

1. A traffic control sign comprising a main compartment and an end compartment, means for permanently illuminating

the main compartment; a translucent wall 20 for the main compartment having a contrasting band across it and traffic instructions lettered adjacent such band, means for intermittently illuminating the end compartment, and a window for the end 25 compartment adapted to define an arrow-head so placed that when both said compartments are illuminated, said arrow-head and said band will form an arrow to point out a direction referred to by said traffic 30 instructions.

2. A sign as defined in claim 1 having an end compartment at each end of the sign and having a plurality of bands across the main compartment, and said end compartments defining either an arrow-head or an arrow-tail for each band. 35

ALFRED ELY.
